ROBERT WILHELM VOIGT, OF DRESDEN, GERMANY, ASSIGNOR TO THE FIRM "UNIVERSALLE" CIGARETTENMASCHINEN-FABRIK J. C. MÜLLER & CO., OF DRESDEN, GERMANY

APPARATUS FOR COLLECTING AND SUPERPOSING GROUPS OF CIGARETTES

Application filed May 21, 1929, Serial No. 364,835, and in Germany May 25, 1928.

In the packeting of cigarettes or like goods a definite number of cigarettes are combined to form a group and delivered to the box or packet. In general several groups are placed in superposed layers in the box or packet and it is necessary therefore to lay the collected groups in superposed layers. This can be effected by suitably delivering them to the packet or box but it is not possible with 10 packets or boxes in which the cigarettes must be inserted from one end. In such cases the groups of cigarettes must be first placed one over the other and the whole of the intended contents pushed into the packet or box by 15 means of a plunger or the like.

The present invention provides a solution of the problem of collecting the separate cigarettes into groups of suitable number and of placing these groups in the desired number of layers so that they can be pushed as 20 a whole into the packet or box.

Many suggestions have already been made for this purpose. The present invention affords a new solution in which the cigarettes 25 fed forwards along a feed band to an abutment or stop after the necessary number to form a group have been collected are raised by means of an elevating device into the path of a plunger or pusher so that by arranging adjacent one another a number of collecting devices and superposing several parallel pusher tracks a suitable number of layers of groups located one above the other may be 30 combined.

Preferably the feed track consists of two parallel bands or belts between which the elevating device moves and over which the cigarettes project laterally with their ends, an upper covering being provided at each cigarette end adjacent the collecting station each of which is formed as an operating lever which during the elevation of the cigarettes is moved by suitably controlled rods so that 40 the ends of the cover leave the cigarettes free to the operating lever.

The invention is illustrated in the accompanying drawings in which Fig. 1 is a side elevation and Fig. 2 a front elevation partly 50 in vertical section on the line 2-2 of Fig. 1.

The embodiment illustrated deals with the packeting of cigarettes of oval cross section.

The separate cigarettes are continuously deposited by known means on the upper flight of two parallel feed bands 1 which are led over the guide pulleys 2 and 3. The guide pulleys 3 on the spindle 4 are driven by a train of gearing 5, 6 from the main shaft 7. The upper flights of the feed bands 1 are moved in the direction of the arrow indicated in Fig. 1 and near the end of the feed track is provided a fixed inclined stop or surface 8 against which the cigarettes strike and by which the cigarettes are dressed in an inclined position.

As is clear from Fig. 2, the ends of the cigarettes project laterally beyond the flights of the feed bands 1. Adjacent the collecting station the cigarettes are covered by covering surfaces 9 which in known manner prevent the piling and rising of the cigarettes. These surfaces form the free ends of bell crank levers 10 which are pivotally mounted about the pivots 11 on the frame A. With the bell crank levers are connected rods 12 which with 75 their forked ends embrace the shaft 7 and are guided thereby. Moreover the rods provide horizontal pivots 13 on which are freely rotatable rollers 14 which track cam discs 15 mounted on the shaft 7. The recesses 16 in 80 these cam discs permit a downward movement of the rods 12 under the action of the springs 17 secured thereto. The bell crank levers 10 are thereby rocked and the covering surfaces 9 moved out of the path of the cigarette ends so that the cigarettes may be elevated.

This elevating movement is effected by an elevating device 18 which consists of an angle member (see Fig. 1) carried by two 90 links 19, 20 which are pivoted at 21, 22 on the bracket B and at 23, 24 are pivotally connected to the elevating device 18.

On the shaft 7 is mounted a cam disc 25 the cam 26 of which raises the elevating device by engaging the roller 27 which is mounted on the lower link 20. These links ensure that in the elevating movement the upper angular surface 18' of the elevating device 18 remains horizontal so that the group 100

of cigarettes resting on this surface can be raised without being disturbed or sliding off.

The cigarettes are raised to the level of a feed track C. After they are raised a plunger or pusher 28 which moves in the direction indicated by the arrow in Fig. 2 moves forward and takes with it the group of cigarettes in the feed channel C.

Several feed bands 1 are arranged adjacent one another and a number of tracks C, C' etc. one above the other. Accordingly the adjacent elevating device 18 which is indicated at the left hand of Fig. 2 in dotted lines can elevate the group of cigarettes fed thereby to the level of the feed track C' so that this group on the further feeding movement to the right is located above the lateral group in the feed track C and the two groups can be fed as superposed layers in known manner into the packet or box held ready for the purpose.

On the elevating movement the downwardly extending angular face of the elevating device 18 forms a stop for the cigarettes arriving on the feed bands 1, so that first of all a number of cigarettes may be allowed to collect which is considerably greater than the number intended to form a group. When the elevating device moves upwards it separates the group and forms an abutment surface for the further forward movement of the already collected cigarettes. Thus in all cases sufficient cigarettes are provided for the formation of the next group.

35 The operating means for the elevating device may be so arranged that in the upward movement it moves in the direction of the longitudinal axis of the cigarettes. Accordingly these cigarettes in such elevating movement remain in their position of rest and the whole group is pushed upwards in the inclined direction of the said longitudinal axis without the separate cigarettes moving from their position. Such an elevating movement can easily be obtained by corresponding adjustment of the links 19, 20 with respect to one another and by a corresponding arrangement of the pivots 21, 24.

I claim,

50 1. Apparatus for collecting and superposing groups of cigarettes comprising a plurality of adjacent feed tracks for the cigarettes, a plurality of collecting devices, a plurality of elevating devices one associated with each feed track, superposed channels for delivering the cigarettes from the different elevating devices and a plurality of pushers in superposed arrangement for feeding such groups along said feed channels.

60 2. Apparatus for collecting and superposing groups of cigarettes comprising a plurality of adjacent feed tracks for the cigarettes, said feed tracks consisting each of parallel bands a plurality of collecting stations each including an inclined stop at the end of each

feed track, a plurality of elevating devices one associated with each feed track and adapted to pass between the parallel bands of each track, superposed channels for delivering the cigarettes from the different elevating devices a plurality of pushers in superposed arrangement for feeding such groups along said feed channels, and a cover for the cigarette ends adjacent the collecting stations each cover formed by an operating lever adapted to be rocked during the operation of the elevating device so as to free the cigarette ends.

3. Apparatus for collecting and superposing groups of cigarettes comprising a plurality of adjacent feed tracks for the cigarettes, said feed tracks consisting each of parallel feed bands, a plurality of collecting devices, a plurality of elevating devices one associated with each feed track, said elevating devices consisting each of an angle member adapted to be moved parallel to itself and in its elevated position to form an abutment and adapted to pass between the parallel bands of each track, superposed feed channels for delivering the cigarettes from the different elevating devices and a plurality of pushers in superposed arrangement for feeding such groups along said feed channels.

4. Apparatus for collecting and superposing groups of cigarettes comprising a plurality of adjacent feed tracks for the cigarettes, said feed tracks consisting each of parallel feed bands, a plurality of collecting devices, a plurality of elevating devices one associated with each feed track, said elevating devices movable in the direction of the longitudinal axes of the cigarettes and adapted to pass between the parallel bands of each track, superposed channels for delivering the cigarettes from the different elevating devices and a plurality of pushers in superposed arrangement for feeding such groups along said feed channels.

In testimony whereof I affix my signature,
ROBERT WILHELM VOIGT.
